[57] CLAIM

The ornamental design for a plural-tipped dispenser for fluids, as shown and described.

DESCRIPTION

FIG. 1 is a perspective view of the plural-tipped dispenser for fluids showing our new design;

FIG. 2 is a left side elevational view thereof, the right side elevational view being identical thereto;

FIG. 3 is a front elevational view thereof, the rear elevational view being identical thereto;

FIG. 4 is a bottom plan view thereof;

FIG. 5 is a top plan view thereof; and,

FIG. 6 is a perspective view showing our new design with the two halves thereof twisted away from one another to alternative positions.
